UNITED STATES PATENT OFFICE.

WILLIAM BARTHOLOMEW, JAMES F. BRODERICK, AND FRITZ BALZER, OF CHICAGO, ILLINOIS, ASSIGNORS TO TROY LAUNDRY MACHINERY COMPANY, LTD., OF CHICAGO, ILLINOIS, A CORPORATION OF NEW YORK.

SAFETY-GUARD FOR CENTRIFUGAL EXTRACTORS.

1,214,988.

Specification of Letters Patent.

Patented Feb. 6, 1917.

Application filed February 18, 1913. Serial No. 749,141.

To all whom it may concern:

Be it known that we, WILLIAM BARTHOLOMEW and JAMES F. BRODERICK, citizens of the United States, and FRITZ BALZER, a subject of the Emperor of Germany, all residing at Chicago, in the county of Cook and State of Illinois, have invented certain new and useful Improvements in Safety-Guards for Centrifugal Extractors, of which the following is a specification.

Our invention relates in general to laundry machinery, and more particularly to centrifugal extractors.

The high speed at which the baskets of centrifugal extractors are rotated renders their use dangerous to careless operators unless such extractors are provided with safety appliances for preventing access to the baskets while they are rotating. In order that such safety devices may fully protect the operators, it is necessary that access should be prevented to the baskets not only while the power is applied to rotate them, but after the disconnection of the driving power and while the baskets continue to rotate by momentum at dangerous speeds.

The primary object of our invention is to provide a centrifugal extractor in which the cover when closed will be locked in closed position while power is applied to rotate the basket, and in which the cover cannot be unlocked while the basket continues to rotate.

A further object of our invention is to provide a centrifugal extractor having a cover for preventing access to the revolving basket, in which power can only be applied to the basket after the cover has been locked, and in which the driving means which necessarily rotates while the basket rotates will be so connected with the cover that it cannot be opened until such driving means have ceased to move.

A further object of our invention is to provide an improved centrifugal extractor, which will be simple in construction and operation, and the use of which will be unattended by any possible injury to the operators.

Our invention will be more fully disclosed hereinafter with reference to the accompanying drawings, in which the same is illus-

trated as embodied in a convenient and practical form, and in which—

Figure 1 is a side elevational view;

Fig. 2, a rear elevation of the upper portion of the casing and parts attached thereto;

Fig. 3, a plan view, a portion of the casing being broken away; and

Fig. 4, a detail vertical section of a modification.

Similar reference characters are used to designate similar parts in the several figures of the drawings.

Reference letter A designates the casing of a centrifugal extractor in which is inclosed the usual revolving basket a. A' designates an annular water ring located around the top of the casing and overlying the space between the casing and basket. a' designates a water-guard projecting upwardly at the rear of the water ring. B designates a suitable support for the casing comprising standards and a base b adapted to be supported upon the floor. C designates a cover closing the top of the casing and thereby preventing access to the inclosed basket. D designates a vertical spindle upon the upper end of which the basket is supported and to which power is applied for rotating the same and thereby rotating the basket. d designates a pulley secured concentrically around the spindle D and which is engaged by a driving belt E. F' and F² designate idler guide pulleys around which the driving belt E passes and by which it is directed to the pulley d and also to a suitable driving pulley to which rotary motion is imparted by any suitable power controlling mechanism. The driving pulley and power controlling mechanism are not illustrated, as they are well known in the art and do not constitute parts of my invention. G designates a suitable bracket supported upon the base b of the standard B and upon which are journaled the idler guide pulleys F', F².

H designates a pulley which is engaged by the driving belt E and consequently is rotated at all times that the basket C is rotated. The pulley H rotates about a vertical axis and is suitably supported upon the frame of the machine so as to freely rotate when the driving belt is in motion. The

top of the pulley H is provided with a laterally extending flange h which is received within a recess k formed in the under surface of a supporting bracket K. An annular supporting plate k' underlies the flange h and is secured to the lower edge of the circular flange around the recess in the bracket K in which is inclosed the flange h on the pulley H. Ball bearings k² are preferably interposed between the under surface of the flange h and the upper surface of the supporting plate K'. L designates a sleeve extending concentrically through the bracket K and also through the top of the pulley H. The bracket K is fixed to the sleeve L in any suitable manner, as by means of a clamp screw l, while the pulley H loosely surrounds the sleeve L. The sleeve L is fixed within a depending tubular portion l' of a bracket L', the latter being supported upon the under surface of the casing A by means of a bar L². The pulley H is hollow and open at its bottom so as to form a chamber within which is inclosed a centrifugal detent comprising a ball H' loosely supported within a seat H² secured to the under surface of the top of the pulley H. The seat H² preferably comprises an annular flange secured to the under surface of the pulley and a cylindrical inwardly tapering flange which surrounds and supports the ball H', as clearly shown in Fig. 1. A rod H³ depends from the ball H' and carries at its lower end a weight h³. The ball H' is provided with a recess h' at its upper surface, which alines with the opening through the fixed sleeve L when the ball H' is in the position to which it is moved by the weight h³ when the pulley H is not rotating. When, however, the pulley is rotating the weight will be swung laterally by centrifugal action into the position shown in full lines in Fig. 1, thereby moving the recess h' in the ball H' out of alinement with the opening in the sleeve L. In order to prevent contact with the pulley H a surrounding shield k³ is provided which is suitably secured at its upper end around the fixed bracket K. The shield k³ is open at its inner side, as shown in Fig. 3, so as to permit the unobstructed contact of the belt E with the pulley.

M designates a reciprocating rod which extends through and is guided by the fixed sleeve L. The upper end of the rod M is pivotally connected to the short arm of a crank lever N, the latter being fulcrumed upon the water-guard a' through the medium of a bracket n. O designates a reciprocating bolt pivotally connected by means of a slot and bolt to the bell crank lever N and extending through horizontally alining openings in ears O' and O² of a bracket secured to the water-guard. The portion of the water-guard intermediate of the ears O' and O² is provided with a slot through

which extends the link P, the latter being pivotally connected at one end to a bracket p fixed upon the cover C at a point eccentric to the pivotal connection between the cover and water ring A' afforded by the hinges c. The opposite end of the link P extends through the water-guard and is pivotally connected to the upper end of a short link R, the latter being formed with, and radially projecting from, a sleeve r which loosely surrounds the rod s supported at its ends by spaced ears on the bracket S, the latter being suitably secured to the water-guard a'.

T designates a spring secured to the bell crank lever N and also to a pin t projecting from the water-guard a', the tension of which tends to oscillate the bell crank lever in a direction to move the bolt O toward the left in Figs. 2 and 3, and to thereby cause the same to pass through a hole p' in the link P when the cover is closed.

The manner of using and operation of our invention are as follows: Assuming that the cover is closed and that the driving power has been disconnected from the belt E so that the latter is not in motion, in order to open the cover the bell crank lever N is oscillated toward the right, thereby withdrawing the bolt O from engagement with the hole p' in the link P, which when the cover is closed alines with the path of movement of the bolt. The cover may then be lifted, thereby moving the link P into the position shown in dotted lines in Fig. 1. The rod M is of such a length that when it is lifted by the movement of the bell crank lever toward the left into locking engagement with the link P when the cover is closed, it will terminate at its lower end just above the ball H', as shown in Fig. 1. When the bell crank lever N is oscillated toward the right to unlock the cover through disengagement with the link P the rod M is reciprocated downwardly, which causes the lower end thereof to pass into the recess in the upper surface of the ball H', such recess alining with the rod M when the ball H' is in the position it assumes when the pulley H is not in motion.

After the articles from which it is desired to extract the water have been placed within the basket and it is desired to apply power to rotate the basket, the bell crank lever N is first swung to the right so as to move its free end from the path of the link P, thereby permitting the cover to be closed and the link P to be drawn into the position shown in full lines in Fig. 1, in which the hole p' therein registers with the bolt O. The bell crank lever N is then permitted to swing to the left, owing to the tension of the spring T which causes the bolt O to pass through the hole p' in the link P. This movement of the bell crank lever elevates

the rod M so that its lower end is disengaged from the recess in the ball H'. Driving power is then applied to the belt E through any suitable power controlling device. The motion of the belt E rotates the pulley H, thereby causing the ball h³ to swing outwardly to the position shown in Fig. 1, owing to the slight eccentric position of the ball H' relatively to the vertical axis of rotation of the pulley H. The swinging of the weight h³ outwardly oscillates the ball H' so that the recess therein is out of alignment with the rod M. It is therefore evident that during the rotation of the pulley H the bolt O cannot be withdrawn from engagement with the link P, inasmuch as the necessary oscillation of the bell crank lever N is prevented, owing to the position of the ball H' obstructing the downward movement 20 of the rod M. The cover of the basket therefore must remain locked in closed position as long as the basket rotates, inasmuch as the pulley H rotates coincidentally with the rotation of the basket pulley d, and while 25 the pulley H rotates, the rod M is locked against the movement requisite to permit the disengagement of the bolt O from the link P.

When the driving power has been disconnected from the belt E and the basket has ceased to rotate, the pulley H has also come to a stop, so that the weight h³ will depend by gravity in such position that the recess h' in the ball H' will align with the lower 35 end of the rod M. The lever N may then be oscillated toward the right so as to disengage the bolt O from the link P, thereby permitting the cover to be raised.

The turnbuckle m permits such adjustment of the rod M as to locate the lower end thereof in such relation with the ball H' that the rod M cannot be moved downwardly, while the pulley H is rotating, a sufficient distance to permit the disengagement 45 of the bolt O from the link P.

In Fig. 4 we have illustrated a slight modification of the eccentrically depending centrifugally operated stop. In this figure a stop U is pivoted at u at one side of the 50 vertical axis of the rod M, and is provided with a depending rod u', at the lower end of which is the weight U'. The operation of this modified form of our invention is substantially the same as that illustrated in Fig. 1, and will be clearly understood without detailed explanation. The rotation of the pulley H causes the weight U' to swing outwardly, as indicated in full lines in Fig. 4, thereby oscillating the stop U to a position 55 beneath the lower end of the rod M so as to prevent the downward movement of the latter, and consequently the operation of the bolt in a direction to unlock the cover. When the pulley ceases to rotate the weight U' 60 will, through the action of gravity, cause the

stop U to assume the position shown in dotted lines in Fig. 4 at one side of the rod M, so that the latter may be depressed and the cover unlocked.

From the foregoing description it will be observed that we have invented an improvement in centrifugal extractors and similar machines, by means of which the cover when closed is positively locked in closed position at all times during the rotation of the basket, whether such rotation is due to the connection of the driving power therewith or to momentum after the disconnection of the power therefrom. The cover, therefore, cannot be unlocked until the basket has ceased to rotate.

While we have illustrated and described our invention as embodied in a centrifugal extractor and have defined the same in the following claims with reference to such embodiment thereof, yet we do not wish thereby to be understood as restricting the application of our invention to centrifugal extractors, but intend thereby to protect it for whatever uses it may be adapted and in whatever forms it may be capable of practical embodiment, and while in the annexed claims we have defined our invention as embodied in a centrifugal extractor, yet it will be understood that we do not intend to be limited to that specific embodiment of our invention, but contemplate embodying it in other machines in which it may be practicable.

What we claim is:

1. In a centrifugal extractor, the combination with a rotary member, of a safety guard for said member, manually operable locking mechanism for retaining said guard in closed position, an element controlling the operation of said locking mechanism, and a stop actuated by centrifugal action to prevent the movement of said element necessary to permit the unlocking of said guard during the rotation of said member.

2. In a centrifugal extractor, the combination with a rotary basket, of a cover for closing said basket, means for rotating said basket, locking mechanism operable when said cover is closed for retaining said cover in closed position, an element controlling the operation of said locking mechanism, and a stop actuated by centrifugal action to prevent the movement of said element necessary to permit the unlocking of said cover during the rotation of said basket.

3. In a centrifugal extractor, the combination with a rotary member, of a safety guard for said member, locking mechanism for retaining said guard in closed position, an element connected to and controlling the operation of said locking mechanism, an oscillatory stop controlling the movement of said element, a weight connected with said stop for oscillating the same into a position to

permit the movement of said element necessary to unlock said guard, and means for subjecting said weight to centrifugal action during the rotation of said member and thereby oscillating said stop into position to prevent the movement of said element necessary to permit the unlocking of said guard.

4. In a centrifugal extractor, the combination with a rotary basket, of a cover for closing said basket, means for rotating said basket, locking mechanism for retaining said cover in closed position, a rod connected to and controlling the operation of said locking mechanism, an oscillatory stop controlling the movement of said rod in a direction to permit the operation of said locking mechanism to unlock the cover, a weight connected to said stop for oscillating the same, and means for subjecting said weight to centrifugal action during the rotation of said basket and thereby oscillating said stop into position to prevent the movement of said rod necessary to permit the unlocking of said basket.

25 5. In a centrifugal extractor, the combination with a rotary member, of a safety guard for said member, locking mechanism for retaining said guard in closed position, a vertical reciprocating rod connected to and controlling the operation of said locking mechanism, a belt for rotating said member, a pulley having a vertical axis engaging said belt and rotating simultaneously with said member, a weight pivotally mounted on said pulley eccentric to its axis of rotation, and a stop actuated by said weight to prevent the movement of said rod necessary to permit the operation of said locking mechanism to unlock said guard during the rotation of said member.

40 6. In a centrifugal extractor, the combination with a rotary basket, of a cover for closing said basket, locking mechanism comprising a reciprocating bolt for retaining said cover in closed position, an element controlling the operation of said locking mechanism, a belt for driving said basket, a pulley engaging said belt and rotating simultaneously with said basket, a weight pivotally mounted on said pulley eccentric to its axis of rotation, and a stop actuated by said weight to prevent the movement of said element necessary to permit the reciprocation of said bolt in a direction to unlock said cover during the rotation of the basket.

60 7. In a centrifugal machine, the combination with a rotary member, of a safety guard for said member, a bolt for locking said guard in closed position, a bell crank lever for reciprocating said bolt, a rod connected with said bell crank lever and reciprocated thereby when oscillated to actuate said bolt, and an obstruction movable by centrifugal action into the path of said rod to prevent the movement thereof necessary to permit

the bell crank lever to unlock said guard during the rotation of said member.

8. In a centrifugal extractor, the combination with a casing, of a rotary basket within said casing, a cover pivotally mounted on said casing for inclosing said basket, a bolt for locking said cover in closed position, a bell crank lever pivotally mounted on said casing for reciprocating said bolt, a rod connected with said bell crank lever and reciprocated thereby when oscillated to actuate said bolt, and an obstruction movable by centrifugal action into the path of said rod to prevent the movement thereof necessary to permit the bell crank lever to unlock the cover during the operation of the basket.

9. In a centrifugal extractor, the combination with a rotary member, of a safety guard for said member, a bolt for locking said guard in closed position, a bell crank lever for reciprocating said bolt, a rod connected with said bell crank lever and reciprocated thereby when oscillated to actuate said bolt, a belt for rotating said member, a pulley engaging said belt and rotated thereby on an axis concentric with the path of movement of said rod, a weight pivotally mounted on said pulley eccentric to its axis of rotation, and a stop actuated by said weight to overlie the end of said rod and thereby prevent the movement thereof necessary to permit the unlatching of said guard during the rotation of said member.

10. In a centrifugal extractor, the combination with a casing, of a rotary basket within said casing, a cover pivotally mounted on said casing for inclosing said basket, a bolt for locking said cover in closed position, a bell crank lever pivotally mounted on said casing for reciprocating said bolt, a rod connected with said bell crank lever and reciprocated thereby when oscillated to actuate said bolt, a belt for rotating said basket, a pulley engaged by said belt and rotated thereby about an axis concentric with the path of movement of said rod, a weight pivotally mounted on said pulley eccentric to its axis of rotation, and a stop actuated by said weight to overlie the end of said rod and prevent the movement thereof necessary to permit the unlocking of said cover.

11. In a centrifugal extractor, the combination with a rotary member, of a safety guard for said member, means for controlling the opening of said guard comprising a bell crank lever and a reciprocating rod connected therewith, and an obstruction movable by centrifugal action into the path of said rod to prevent the movement thereof necessary to permit the bell crank lever to move in a direction to permit the opening of said guard.

12. In a centrifugal extractor, the combination with a rotary member, of a safety guard for said member, means for control-

ling the opening and closing of said guard comprising a reciprocating rod, a belt for rotating said member, a pulley engaging said belt and rotated thereby on an axis concentric with the path of movement of said rod, a weight pivotally mounted on said pulley eccentric to its axis of rotation, and a stop actuated by said weight to obstruct the movement of said rod into said pulley and therefore to prevent the movement thereof necessary to permit said guard to be opened.

13. In a centrifugal extractor, the combination with a casing, of a rotary basket in said casing, a cover pivotally mounted on said casing for controlling access to said basket, driving means for rotating said basket, means for controlling the opening and closing of said cover comprising a recipro-

cating rod, a stop movable into and out of the path of movement of the rod, said stop 20 comprising a weight actuated by gravity when the basket is stationary to permit the movement of said rod necessary to the opening of the cover and actuated by centrifugal force when the basket rotates to prevent the 25 movement of the rod necessary to the opening of said cover, a rotary carrier for said stop, and means for rotating said carrier in unison with the rotation of the basket.
